SOOT BLOWER

Allan Murray Wilson, Clydebank, Scotland

Application June 6, 1939, Serial No. 277,667
In Great Britain June 17, 1938

10 Claims. (Cl. 192—142)

This invention relates to so-called "soot-blowers" which are used in association with steam-boilers and other heat exchangers for the purpose of periodically ejecting cleaning fluid (usually steam) on tubes and other parts to remove soot, scale and other matter likely to be deposited thereon.

The invention relates in particular to soot-blowers which for their operation require a to-and-fro axial movement to be imparted to one of their working parts, usually the fluid ejector.

An object of the invention is to provide an improved operating assembly including a motor for imparting to the working part concerned the requisite to-and-fro axial movement.

Another object is to provide an operating assembly comprising a unidirectional rotary drive, for example an electromotor drive, a reversible power-transmitting connection driven by said drive, reversing mechanism interposed between said drive and said connection and means actuating said reversing mechanism after a predetermined extent of operation to reverse the direction in which said connection is driven.

Another object is to provide reversing mechanism comprising opposed bevel pinions, which are journaled co-axially of a unidirectionally rotary driving shaft and which are respectively provided with clutch elements, a bevel gearwheel which meshes with both bevel pinions and which is connected to the said power-transmitting connection, and a double-acting clutch driven by said shaft and displaceable thereon to engage said clutch elements alternatively.

Another object is to provide a device which cuts out the unidirectional rotary drive when the cleaning-fluid ejector occupies the inoperative position on completion of a predetermined number of strokes.

Another object is to provide clutch mechanism including an element displaceable into alternative positions in which the fluid-cleaning ejector is caused to advance and withdraw respectively, a coupling between ejector-operating gear and said element to effect the requisite displacement thereof, said coupling being actuated initially by the ejector-operating gear, and a device which accumulates energy in the initial actuation of said coupling and thereafter applies such energy to the completion of the actuation of said coupling.

Other objects of the invention will be apparent from the following description and claims.

The invention will now be described by way

of example with reference to the accompanying drawings in which:

Fig. 1 is a plan of a soot-blower, parts on which the blower is mounted being shown in section.

Fig. 2 is a sectional plan of parts of the blower-operating assembly, Fig. 2 being drawn to a larger scale than Fig. 1.

Fig. 3 is a sectional elevation in the direction of the arrow III, Fig. 2.

Fig. 4 is a section on the line IV—IV of Fig. 1, Fig. 4 also being drawn to a larger scale than Fig. 1.

Fig. 5 is a section on the line V—V of Fig. 2.

Fig. 6 is a section on the line VI—VI of Fig. 5.

Figs. 7 to 11 are diagrams illustrative of the action of switch-operating parts.

Fig. 12 is a diagram illustrative of electrical components provided in association with the soot-blower.

Fig. 13 is an elevation of a soot-blower having its operating assembly arranged in a different manner from that according to Figs. 1 to 4, and Fig. 14 is a plan of Fig. 13.

Fig. 15 is an elevation of a soot-blower having its operating assembly arranged in yet a different manner from that according to Figs. 1 to 4, the arrangement according to Fig. 15 involving operation from a remote location.

Referring firstly to Figs. 1 to 4, the soot-blower according thereto comprises a casing formed mainly of three stationary parts 20, 21, 22 which are rigidly inter-connected in axial co-relationship. The part 20 is attached to a so-called wall-box 23 which is embedded in the wall 24 of a steam-boiler. The part 20 is formed with a branch 25 which serves for the supply of cleaning steam to the soot-blower. The steam ejector of the soot-blower consists of a nozzle 26, which is shown in the example as being double-ported (Fig. 1). The nozzle 26 is secured to one end of a nozzle tube 27 which forms an extension of another tube 28. The nozzle tube 27 is formed with steam-inlet ports 29 which can be brought into register with ports 30 in permanent communication with the steam-inlet branch 35.

The extension tube 28 encloses a pair of interengaging screwed elements, one of which is a nut 31 secured in the tube 28 and the other of which is a screwed shaft 32 which is rotatable in a stationary location. The screw-threaded shaft 32 receives to-and-fro rotational motion through screw-gears 33, 34 of which the gear 33 is secured to the shaft 32 and of which the gear 33 is secured to a shaft 35. The screw-gears 33, 34 are journaled in a gear case 36 which is adjust-

able about the common axis of the casing 20, 21, 22, the tubes 27, 28 and the rotatable parts 32, 33.

The screw-threaded shaft 32 and nut 31 work in combination with a cam device which controls the angular setting of the tube 28 and consequently the nozzle 26. In the example, the cam device consists of a cam slot 31a, 31b, which is formed in the casing part 22 and the follower of which is a pin or roller 31' mounted on the tube 28. The portion 31a of the cam slot is straight whereas the portion 31b is helically or otherwise inclined. The arrangement is accordingly such that if the ejector unit consisting of the parts 26-28 is caused to move axially by rotation of the screw-threaded shaft 32, the cam device will act to maintain the said unit against angular motion while the pin or roller 31' is in the portion 31a but will permit or cause angular motion when the pin or roller 31' is in the portion 31b.

The ports 29 and 30 constitute valve means which operate automatically in the operation of the blower to open the supply of steam while the ejector 26 is advanced axially into an operative zone beyond the wall box 23 and to shut off the supply while the ejector is retracted into an inoperative zone (see Fig. 1) in which it is sheltered from the heat of the furnace of the boiler. The arrangement is such that the ejector is advanced and retracted axially through the inoperative zone but is also turned angularly or rotationally as it advances or is retracted through the operative zone.

The soot-blower parts so far described are known per se and accordingly the construction and operation thereof need not be described herein in further detail.

A screw threaded shaft 37 constituting a reversible blower-operating member is connected by a flange coupling 38 to the gear shaft 35. In the example under consideration the shaft 37 is horizontally arranged. Secured to the shaft 37 is a pinion wheel 39 which constantly meshes with two coaxial but diametrically opposed pinions 40a, 40b journaled on a horizontal clutch shaft 41 which is driven unidirectionally by a small electric motor 42, for example a squirrel-cage motor of $\frac{1}{8}$ brake-horse-power and rotatable at 1400 revolutions per minute. The speed of the motor is reduced by reduction gearing which is not shown in the drawings but which is contained in a casing 43 forming part of the same structure as the motor, the reduction ratio being such that the clutch shaft 41 is rotated unidirectionally at about 50 revolutions per minute. The motor is mounted in juxtaposition to the soot-blower casing 20, 21, 22 with the motor axis parallel to the casing axis (Fig. 1). The motor and reduction-gear structure is supported by a bracket 44 on the boiler wall. The operating shaft 37 is journaled in a casing 45 and the pinion gears are housed in a gear casing 46 which also is secured to the bracket 44 and to which the casing 45 is secured.

Each of the opposed pinions 40a, 40b has an inwardly facing clutch 47 or 48, and a double-acting clutch 49 is disposed on the shaft 41 between said pinions to engage with the pinion clutches alternatively. The double-acting clutch is feathered at 50 to the clutch shaft 41 so as to rotate therewith, but the double-acting clutch 49 is slidable along the shaft 41 under the control of a clutch lever which is composed of three lever arms 51, 52, 53 and is fulcrumed in the gear

casing 46. The lever arm 51 is a fork which engages an annularly grooved portion 54 of the double-acting clutch 49. The second lever arm 52 is pivotally attached to a trigger rod 55 which is axially slidable in bearings provided for it in the casings 45, 46. The trigger rod 55 is provided with two spaced triggers 56, 57 which are arranged to co-operate with an intermediate striker 58 on a nut 59 (see Figs. 2, 5 and 6) which is in screw-threaded engagement with the operating shaft 37. A guide 60 secured to the casing 45 engages the striker 58 and thus maintains the nut 59 against rotational movement but permits the nut to move axially in one or other direction according to the direction in which the operating shaft 37 is rotated. The nut 59 constitutes an automatic reverser which acts on the clutch 49 through the triggers 56, 57 and the rod 55. The third lever arm 53 is a short projection presenting inclined faces which meet at an apex. This projection co-operates with a similarly formed projection 61 on a plunger 62 which is constantly pressed by a spring 63 and which is guided for movement to and from the projection 53 in a guide box 64.

The clutch parts are so designed that, when the double-acting clutch 49 is passing through its mid-position in relation to the two pinion clutches 47, 48 a small clearance space is left between the teeth of the double-acting clutch and the teeth of the two pinion clutches (see Fig. 2).

So far as concerns the parts already described with reference to the drawings, the ejector unit 26-28 occupies substantially the retracted position in which it is shown in Fig. 1 when the soot blower is inoperative, and the nut 59 on the operating shaft 37 then occupies substantially the position in which it is shown in Figs. 2 and 6. The double-acting clutch 49 is then so located that its teeth are fully in mesh with the clutch teeth 48 of the pinion 40b.

When the motor 42 is started, the clutch shaft 41 is rotated and rotates the operating shaft 37 in the direction to advance the ejector unit 26-28 from its retracted position, so that the nozzle 26 will advance from the wall box 23 into the operative zone. At the same time, the nut 59 will be caused to advance along the shaft 37 towards the trigger 57. As the nozzle 26 nears its fully advanced position, the striker 58 will engage the trigger 57; and so the trigger rod 55 will be displaced and will force the lever arm 52 to turn about its fulcrum and cause the lever arm 51 to withdraw the double-acting clutch from engagement with the pinion clutch 48, thus freeing the pinions 40b and 39 from the motor drive. In consequence the operating shaft 37 and parts operated therewith will instantly come to rest. However, the movement of the clutch lever 51-53 will be sufficient to bring the apex of the projection 53 just past the dead centre position in relation to the co-operating projection 61, with the result that the compressed spring 63 will force the clutch lever to continue its movement and bring the double-acting clutch into full engagement with the clutch teeth 47 of the opposite pinion 40a. Thus, a reversing action of the clutch parts is automatically brought about.

After reversal, the pinion 40a, acting through the pinion 39, will cause the operating shaft 37 to be rotated in the opposite direction, so that the ejector unit will be retracted from its advanced position and the nut 59 will be caused to move axially towards the trigger 56. When the ejector

unit nears its fully retracted position the striker 58 engages the trigger 56 and displaces the trigger rod 55 in the direction to cause the double-acting clutch 49 to be retracted from engagement with the clutch teeth 47 of the pinion 40a. When the apex of the projection 53 has just passed the dead centre (as shown in Fig. 2, the lever then turning in the direction of the arrow) the compressed spring 63 acting through the projection 61 on the projection 53 will cause the clutch lever to continue its movement sufficiently to bring the double-acting clutch 49 into full engagement with the clutch teeth 48 of the pinion 40b. Thus, another reversing action is brought about.

The foregoing procedure will continue until the motor is stopped.

It will have been noted that, as each stroke of the ejector unit 26-28 is nearing its end, the action of the nut 59 and striker 58 upon the trigger rod 55 and clutch lever 51-53 builds up sufficient energy by compressing the spring 63 to ensure that the reversing action of the double-acting clutch 49 will be completed after the clutch-driven parts have been cut-off from the motor drive. In effect, the double-acting clutch following the completion of any stroke of the ejector unit is automatically brought into a condition to transmit the drive to the said unit and other driven parts in the next stroke, whether or not that stroke in fact takes place.

Provision is made for varying the stroke of the steam-ejecting nozzle 26. In the example, the provision consists in arranging the trigger 57 adjustably on the trigger rod 53 and providing a pinching screw 57a (Fig. 6) to secure the trigger 57 in its position of adjustment. This ensures that it is the place of reversal at the end of the advance stroke of the nozzle which is varied, the retracted position remaining constant. By making such provision, the nozzle stroke is variable between a maximum of about 7 inches and a minimum of about 3 inches.

In order that the working parts of the soot-blower and of the operating assembly can be turned manually, a hand-wheel 65 is secured to one end of the clutch shaft 41.

Provision is made whereby stoppage of the blower-operating motor occurs automatically after completion of a predetermined number of nozzle strokes, this number in the example being six strokes. The arrangement is such that stoppage occurs only when the ejector has reached its fully retracted position following which, as already explained, the double-acting clutch 49 automatically re-engages the appropriate pinion clutch. This ensures that, following stoppage of the motor, the clutch mechanism is set all in readiness for the switching-on of the motor.

The mechanism for causing the requisite timed stoppage of the motor is operated by the reversing nut 59. As shown in Figs. 2, 5 and 6, the mechanism includes two striker pins 66, 67 arranged at different levels and horizontally offset from one another on the nut 59. These pins co-operate with a star wheel 68 which they are adapted to rotate intermittently, the star wheel having three arms equispaced 120° apart in conformity with the requirement that the nozzle shall perform six strokes. The star wheel 68 is secured to a shaft 69 to which a cam 70 is secured. This cam has an active surface (see Fig. 3) which is formed with a uniform displacement contour rising in a curve from a point of minimum height to one of maximum height, both points being interconnected by a steep drop at 70a. The follower 75

of the cam consists of a tappet 71 with a cam-engaging roller 71a (Fig. 2), the tappet being forced towards the cam by a spring 71b. There is also secured to the cam shaft 69 a locating disc 72 which is formed with six equispaced notches 72a. A spring-urged detent 73 (Fig. 3) co-operates with the notches 72a and is thus adapted to locate the cam in the successive positions into which it is turned by the action of the pin 66, 67.

The tappet 71 constitutes a mechanical support for two bridge switches S' and S², respectively co-operating with pairs of contacts C', C' and C², C² (Figs. 3 and 5). The cam 70, disc 72, switches S', S² and contacts C', C² are disposed in a casing 14 which is secured to the casing 45 of the operating shaft 37 and parts thereon. The cam shaft 69 is journaled in the casing 14 and extends therefrom into the proximity of the reversing nut 59. The casing 14 is closed by a cover plate 75 (removed in Fig. 3). The respective contacts C', C² are electrically connected to four terminals T (Figs. 3 and 5), the electric leads from these terminals not being shown in the drawings.

The striker pins 66, 67 serve to impart to the cam 70 intermittent rotation in steps of 60° each and by virtue of this rotational motion the cam 70 controls the operation of the switches S', S². The operation of the striker pin 66, 67 will be described hereinafter with reference to Figs. 7 to 11.

Referring now to Fig. 12, there are diagrammatically represented therein an assembly of electric and electro-magnetic components serving for the control of the starting and stopping of the blower-driving motor 42.

Referring to Fig. 12, R¹ and R² represent two electro-magnetic relays so connected in the electric circuit of the motor 42 that when either or both are closed the motor is thereby completely connected to the mains M and is thus in operation. The two switches S¹, S², the cam 70, and the tappet 71 mechanically interconnecting the switches to operate in unison are also represented. P¹ represents a starting push-button by depression of which the motor is started. P² represents a resetting push button by depression of which the electric and electro-magnetic components are reset in condition for starting the motor should the blower have become stopped in the course of its sequence of operations.

The assembly of electric and electro-magnetic components diagrammatically represented and their connections are not claimed and moreover are known to those conversant with electrical control systems, and therefore details thereof are neither shown in the drawings nor described herein.

The said assembly operates normally as follows: When the blower is not in use and is set in readiness for operation, both relays R¹, R² are open, the switch S¹ also is open but the switch S² is closed; this condition is represented by the drawings. To put the blower in operation, the push button P¹ is depressed, the effect of which is that both relays R¹, R² close and the motor starts. The shaft 69 is now caused to rotate step-by-step, each step following a reversal action by the clutch 49. Each step of the shaft 69 causes the cam 70 to displace the tappet 71 and switches S¹, S², each of which is adapted to maintain sliding contact with the respective contacts C¹, C² during a predetermined extent of its displacement. At an intermediate state, the switch S¹ is closed, but this has no effect on the

other components shown. Next, the switch S^2 is opened, and the only effect of this is to cut-out the coil of the relay R^1 , which instantaneously opens. The relay R^2 however remains closed. Finally, when the drop $70a$ of the cam reaches the tappet 71 , the latter snaps back into its initial position under the action of spring $71b$, thus closing the switch S^3 and opening the switch S^1 . The effect of this is that the coil of the second relay R^2 is cut out, and this relay also opens, so that the motor circuit is broken and the motor stops.

The drawings illustrate the blower parts at the instant after the double-acting clutch 49 has passed through its mid-position and is on its way to engage the pinion clutch 48 in readiness for the next cycle of operations. At the instant illustrated, the tappet 71 has encountered the drop of the cam 70 and snapped into the position in which the motor circuit is open and the motor stopped.

The action of the striker pins $66, 67$ will now be described with reference to Figs. 7 to 11 as starting from the position in which the parts operated by said pins are shown in the drawings; that is, as from the beginning of a complete cycle of operations.

Fig. 7 shows the two pins $66, 67$ starting to move towards the right (that is, in the direction of movement of the striker 58 towards the trigger 57 as viewed in Fig. 6). The steam-ejecting nozzle 26 is then starting to advance from its inoperative position. It will be seen that the top pin 66 will move clear of the star wheel 68 (on the cam shaft 69) whereas the bottom pin 67 will engage it.

Figs. 8 and 9 show how the top pin 66 passes clear of the star wheel 68 and how the bottom pin 67 engages the star wheel and turns it 60° counter-clockwise. The pins $66, 67$ idly continue their motion to the right until the double-acting clutch 54 is changed over, the nozzle 26 then being fully advanced. Thereafter, the pins $66, 67$ return to the left.

Fig. 10 shows that, on the return of the pins, the upper pin 66 will engage the star wheel whereas the bottom pin 67 will move clear thereof. Fig. 11 shows the upper pin turning the star wheel through a further 60° counterclockwise, the turning action being completed when the extreme Fig. 7 position is again reached. At this position the clutch 54 is again changed over. Thereafter, the pins $66, 67$ move towards the right and the nozzle again advances.

Thus, in one complete movement of the pins to the right and back again to the left, the star wheel receives in all 120° from their successive actions. Therefore, when three of these complete movements have been performed (that is, six strokes of the nozzle) the star wheel and the switch cam 70 have turned through 360° , and so the drop of the cam becomes effective. At that instant, the switch mechanism operates to cut-out the blower-operating motor as already described with reference to Fig. 12. The pins and the starwheel then occupy their Fig. 7 position.

In the arrangement according to Figs. 1 to 4, the motor 42 is arranged in juxtaposition to the soot-blower proper with the motor axis parallel to the axis of the ejector unit $26-28$ and the parts associated therewith, the reversing mechanism contained in and associated with the casing 45 being arranged to cross perpendicularly from the gear casing 46 to the soot-blower. There is

the usual blower mounting 23 on the boiler wall and a separate mounting 44 thereon for the motor and associated blower-operating parts. The arrangement may however be such that need for such a separate mounting is obviated. For example, one such other arrangement is illustrated by Figs. 13 and 14, which will now be described.

Referring to Figs. 13 and 14, in the arrangement illustrated thereby, the motor 42 and clutch gearing associated therewith are arranged above the soot-blower proper with their axis cross-wise of the axis of the blower, the axis of the shaft 35 and the parts in the casing 45 being in this arrangement parallel to the blower axis. The individual parts are in general the same as in accordance with Figs. 1 to 4 and the exposed parts are denoted by the same reference numerals. However, as regards the gearing interconnecting the shafts 32 and 35 , as these shafts are now parallel, screw-gears such as $33, 34$ (Fig. 4) are no longer employed but are replaced by any of the various forms of gearing suitable for transmitting a drive between parallel shafts without slip. The motor and gear casing are mounted in the arrangement according to Figs. 13 and 14 on a bracket 80 secured to the casing part 20 , so that the motor, clutch gearing and reversing mechanism require for their accommodation substantially no more space on the boiler wall than a corresponding hand-operated soot-blower.

In the arrangements already described, the motor forms part of the same structural assembly as the soot-blower proper and the intermediate gearing. The arrangement, however, may be such that the soot-blower alone is mounted in the appropriate position on the boiler wall while the motor and clutch gearing are mounted in a remote location; for example, at some convenient place, say, on the floor. An example of such an arrangement is illustrated by Fig. 15.

Referring to Fig. 15, the parts of the soot-blower proper and the operating assembly are substantially the same as already described with reference to Figs. 1 to 4, and accordingly the exposed parts in Fig. 15 are given the same reference numerals. As shown, the soot-blower proper is arranged high above the motor, clutch gearing and reversing mechanism. The casing 45 is so arranged that the shaft 35 is vertical. Correspondingly, the casing 45 and the mechanism contained in and associated therewith is arranged vertically upon the clutch gear case 46 . The shaft 35 , instead of being connected directly to the coupling 38 on the operating shaft 37 , is connected thereto through shafting $90, 91$, the respective parts of which are universally coupled together at 92 . The motor and gear casing are mounted on a sole-plate 93 .

In any of the arrangements described, there may be provided in association with the operating shaft 37 , for operation thereby, an indicator (not shown) comprising a pointer which moves to-and-fro along a stationary graduated scale to indicate the position of the ejector in its range of movement. Such a pointer may be on the nut 59 .

I claim:

1. A sootblower-operating assembly comprising a unidirectional rotary motor drive, a reversible power-transmitting connection driven by said drive, a reversing clutch interposed between said drive and said connection, means operatively connected to said power-transmitting connection for actuation thereby about the end of each one of

several recurring periods of operation of said connection to actuate said clutch and thus reverse the direction in which said connection is driven and means for switching-off said drive, said switching-off means being operatively connectible to said clutch for operation thereby to effect switching-off on completion of a plurality of said periods.

2. A sootblower-operating assembly comprising a unidirectional rotary motor drive, a reversible power-transmitting connection driven for a series of periods by said drive, reversing mechanism interposed between said drive and said connection, means actuating said reversing mechanism at the end of each of said periods to reverse the direction in which said connection is driven and means operated under the control of said reversing mechanism to switch-off said drive on completion of said series of periods.

3. A sootblower-operating assembly comprising a unidirectional rotary motor drive, reversing mechanism comprising opposed bevel pinions journalled coaxially of said drive and respectively provided with clutch elements and a double-acting clutch driven by said drive and displaceable axially thereof to engage said clutch elements alternatively, a bevel gearwheel meshing with both said bevel pinions, a reversible power-transmitting connection driven for a series of periods by said gearwheel and including a rotatable screw-threaded shaft, a nutlike member engaging said shaft, means constraining said member to travel along said shaft on rotation thereof throughout each of said periods, and a trigger assembly adapted for operation by said nutlike member at opposite ends of the travel of said member to actuate said double-acting clutch at the end of each of said periods to reverse the direction in which said connection is driven and means operated under the control of said reversing mechanism to switch-off said drive on completion of said series of periods.

4. A sootblower-operating assembly comprising a unidirectional rotary motor drive, a reversible power-transmitting connection driven by said drive, reversing mechanism including a reversing clutch interposed between said drive and said connection, said clutch being driven by said drive, gears respectively arranged to rotate said connection in opposite directions, said clutch being adapted for alternative engagement with said gears, means adapted to bring said clutch into engagement with one of said gears after a predetermined extent of operation of said connection through the other of said gears, a device adapted to switch-off said drive and means operatively connectible with said clutch so as to be operated by successive transpositions thereof to actuate said device and effect switching-off on completion of a predetermined plurality of such transpositions.

5. A sootblower-operating assembly comprising a unidirectional rotary motor drive, a reversible power-transmitting connection driven by said drive, reversing mechanism including a reversing clutch interposed between said drive and said connection, said clutch being driven by said drive, gears respectively arranged to rotate said connection in opposite directions, said clutch being adapted for alternative engagement with

5 said gears, means adapted to transpose said clutch from one of said gears to the other after each of recurrent periods of operation of said connection, a device adapted to switch off said drive and means operated by said connection to operate said device on completion of a predetermined plurality of such periods of operation.

6. A sootblower-operating assembly comprising a unidirectional rotary motor drive, a reversible power-transmitting connection driven by said drive and applicable to the sootblower, reversing mechanism interposed between said drive and said connection, means adapted to actuate said reversing mechanism at the end of periods of operation by said drive of said connection to reverse the direction in which said connection is driven, a device adapted to switch off said drive and means for operating said device on completion of a predetermined plurality of said periods of operation of said connection.

7. A sootblower-operating assembly comprising a unidirectional rotary motor drive, a reversible power-transmitting connection between said drive and the sootblower, said connection including a rotatable screw-threaded shaft, a nutlike member engaging said shaft, means constraining said member to travel along said shaft on rotation thereof in either direction, a trigger assembly adapted for operation by said nutlike member to effect reversal of said connection at opposite ends of the travel of said member, so that said shaft performs recurrent periods of rotation in successively opposite directions, and mechanism operated by said nutlike member to switch off said drive on completion of a predetermined number of said periods.

8. A sootblower-operating assembly comprising a unidirectional rotary drive, a power-transmitting connection, including reversing mechanism between said drive and the sootblower, a member driven to-and-fro by a part of said connection, a cam operated stepwise by said member so as to perform a plurality of operations corresponding to a predetermined cycle of operations of the sootblower, and means for switching off said drive under the control of said cam on completion of said plurality of operations.

9. A sootblower-operating assembly comprising a unidirectional rotary drive, a power-transmitting connection including reversing mechanism between said drive and the sootblower, said connection including a rotatable screw-threaded shaft, a nut-like member engaging said shaft, means constraining said member to travel along said shaft on rotation thereof in either direction, a cam operated stepwise by said nutlike member so as to perform a plurality of operations corresponding to a predetermined cycle of operations of the sootblower and means for switching off said drive under the control of said cam on completion of said plurality of operations.

10. A sootblower-operating assembly as claimed in claim 7 wherein the said trigger assembly comprises an axially displaceable trigger rod carrying spaced triggers and a striker on said nutlike member and intermediate said triggers, and wherein one of said triggers which effects reversal of the power-transmitting connection is adjustable to vary the duration of said operation.

ALLAN MURRAY WILSON.
